2,653,679

AUTOMATIC LEVELING MECHANISM FOR
HOISTING TRUCKS

Arthur S. Hamilton, Jr., Brighton, N. Y.

Application October 23, 1951, Serial No. 252,753

12 Claims. (Cl. 187—9)

This invention relates to a hoisting truck of the type provided with a load support or table that can be raised or lowered to position a load at any level within the limits of the truck, and has for its purpose to afford means for automatically raising or lowering the support, stopping such movement when the load shall have reached a predetermined level and automatically resuming the movement when the load shall have been reduced or increased in height respectively, depending on whether the load is being raised or lowered.

A further purpose of the invention is to afford mechanism for automatically raising a load support of a truck intermittently through uniform distances so that lifts or sheets of material comprising the load can be removed from the top and the support automatically raised to bring successive portions of the load to the predetermined level for convenient removal of lifts or sheets onto a cutter table or the like onto which the sheets are to be placed.

An additional object of the invention is to provide a truck with electrical mechanism which automatically raises or lowers sheets or lifts of material through predetermined distances successively, governing the operation of the automatic mechanism by the position of the topmost portion of the load in relation to the predetermined level as determined by a beam of light and photocell onto which the beam is reflected.

A more specific purpose of the invention is to accomplish the desired objectives by the provision of a vertically adjustable photocell that is operatively associated with electrical control mechanism which functions automatically to stop movement of the load upwardly when a beam of light striking the elevating load is reflected onto the photocell, and to stop movement of the load downwardly when the load moves beneath the path of the beam of light which is then no longer intercepted and therefore not reflected onto the photocell.

Thus the load support or table can be elevated to the desired level to permit removal of sheets or lifts onto a cutter table by sliding them off from the stack onto the cutter table, and after a lift or number of sheets are removed, the load is automatically elevated until the top of the load is at the original level and intercepts the beam of light, stopping further movement, this operation being repeated as each lift or series of sheets are removed from the top of the load, and on lowering, the reverse operation takes place since the light beam striking the load is reflected onto the photocell and causes the load support to move

downwardly until the top of the load is beneath the light beam, stopping further movement until an additional lift or additional sheets are added to the top of the load, again intercepting the light beam and reflecting it, to repeat the cycle.

Still another object of the invention is to provide automatic electrical raising and lowering mechanism with controlling devices that enable a load to be raised or lowered by manual control, or to be raised or lowered automatically by means that effects intermittent movements of the load support upwardly or downwardly, stopping it whenever the load reaches a predetermined position and its upper portion is in the path of or positioned beneath a light beam respectively, thus moving the support upwardly or downwardly automatically in preadjusted increments.

An additional purpose of the invention is to afford efficient and practical control mechanism including a vertically adjustable housing containing lamp mechanism including a lamp, reflector, and condensing lens operable to project a beam of light toward the load and a condensing lens which receives the beam of light when the latter is reflected from the load and directs it onto a photocell in the housing for operating the control mechanism.

A further object of the invention is to afford electrical mechanism for either manually controlling movement of the load support or table upwardly or downwardly through any distance, or permitting such electrical mechanism to be governed through an arrangement of electrical circuits such that a photocell functions to operate the electrical mechanism and move the load support upwardly or downwardly automatically through successive predetermined distances, dependent upon the vertical positioning of the photocell.

To these and other ends, the invention consists in the construction and arrangement of parts that will appear clearly from the following description when read in conjunction with the accompanying drawings, the novel features being pointed out in the claims following the specification.

In the drawings:

Fig. 1 is a view in side elevation illustrating a truck constructed in accordance with a preferred embodiment of the invention;

Fig. 2 is a rear elevation of the same;

Fig. 3 is an enlarged elevation showing the mechanism appearing at the upper part of Fig. 2, with the front of the housing of the electrical control means removed to show the interior thereof;

Fig. 4 is a view in side elevation of the parts appearing at the upper portion of Fig. 3;

Fig. 5 is a view in rear elevation of the vertically adjustable lamp mechanism and photocell;

Fig. 6 is a vertical sectional view through the lamp housing;

Fig. 7 is a vertical sectional view showing the photocell and vertically adjusting means for the lamp mechanism and photocell;

Fig. 8 is a horizontal sectional view on line 3—8 of Fig. 7;

Fig. 9 is an enlarged detail perspective view of the adjustable locking device which holds the lamp mechanism and photocell in their vertically adjusted positions;

Fig. 10 is a diagrammatic view showing the light beam projecting means in relation to the reflecting load and photocell, and

Fig. 11 is a diagrammatic view of the circuits leading to the hoist motor and electrical control means which are governed either by hand, or automatically by the photocell, the photoelectric relay control switch and "automatic" selector switch being shown in position for automatic raising, and the main switch and "hand" selector switch being shown in "off" positions.

Referring more particularly to the drawings in which like reference numerals throughout the several views indicate the same parts and to Figs. 1 to 3 inclusive, 1 designates the base of a truck provided with the usual floor-engaging wheels 2 and 3, handle 4 for moving the truck over a floor, and uprights 5 upon which is mounted for vertical travel the load support or table 6 comprising a fork that is suitably guided on the uprights 5 and carries a sprocket 7 rotatably mounted thereon and engaged by the operating chain 8 which travels around said sprocket 7 and has one end connected to the motor housing at 9. The motor housing is shown as suspended from the top of the truck by a hook 11, while the portion of the chain 8 adjacent to the connection 9 extends downwardly and thence upwardly in a loop, see Fig. 2, thence around a sprocket wheel 12 that is connected to and driven by the hoist motor 13, and thence downwardly and around sprocket wheel 7 carried by the load support 6 and after leaving sprocket 7 the chain 8 extends upwardly and is connected to hook 14 which is suspended from the cross-member 15 at the top of the uprights 5, and from which the previously mentioned hook 11 is also supported. Instead of suspending the hoist motor and chain by the hooks 11 and 14, they may if preferred be permanently and rigidly attached to the top of the frame.

The structure thus far described is part of a conventional and known hoisting mechanism and forms no part of the present invention, which has to do with the electrical control means to hoist motor 13 for controlling the same either manually or automatically, and which will now be described in detail.

In the conventional operation of hoist motor 13, which is controlled by a reversing drum switch 16, see Figs. 4 and 11, the switch is operated manually through a rock arm 17 which is pivoted at 18 on a stationary bracket and in turn connected by link 19 to the reversing switch arm, so that the load support or fork 6 is moved upwardly or downwardly by operating the rock arm 17 in one direction or the other manually, and the present invention has to do with electrical means for operating said rock arm 17 to control the hoist motor, such electrical means being so constructed and arranged that the load support

can be moved automatically upwardly or downwardly through successive increments of distance whereby the height of the load automatically controls movement of the hoist motor by stopping the motor when the load moves upwardly a predetermined distance and automatically starting the motor again when a lift or sheets have been removed from the pile, or reversely, stopping the hoist motor when the load moves downwardly a predetermined distance following which the hoist motor is automatically started when the height of the load is increased as by piling a lift or additional sheets thereon, or the load can be raised or lowered by manual control when desired.

15 These results are accomplished through a photocell that is in the path of a reflected beam of light which strikes the top portion of the load on the support or fork and is reflected back onto the photocell when the load is at such elevation that its top portion is in the path of the beam of light, and under this position of the load, the hoist motor is automatically stopped if the load is moving upwardly and automatically started if the load is moving downwardly. Thus 20 when the load is traveling upwardly and reaches a point where it intercepts the beam of light, the hoist motor is automatically stopped and remains stopped until a lift or sheets have been removed from the top of the load sufficiently so that the beam or light is no longer reflected onto the photocell, whereupon the hoist motor is automatically started and the load travels upwardly through the predetermined distance. The reverse operation takes place when the load is traveling 25 downwardly, the hoist motor operating to move the load downwardly while the load is in the path of the beam of light, and when the load has moved downwardly far enough so as no longer to lie in the path of the beam of light and reflect it onto the photocell, the motor is automatically stopped and remains stopped until a lift or sheets have been added to the load sufficiently to intercept the beam of light, whereupon operation of the hoist motor is resumed to 30 continue downward movement of the load support or fork.

In order to effect such movements, the rock arm 17 which controls the reversing switch to the hoist motor has operatively connected thereto solenoids 21 and 22 respectively, see Figs. 4 and 11, which when actuated move the rock arm 17 from neutral or "off" position in a direction to operate the hoist motor to move the load support upwardly or downwardly as the case may be. Solenoids 21 and 22 are controlled by suitable switches whereby they may be actuated automatically to move the load upwardly or downwardly in accordance with the position of the load with respect to a vertically adjustable beam of light which effects operation of a photoelectric relay in the manner that will now be described in detail.

Solenoids 21 and 22 are governed from switches 23, 24 and 25 respectively, the main or central switch indicated at 24 being adjustable to determine whether the operation of the hoist motor is to be automatic or manual. Switch 24 is shown in Figs. 3 and 11 in the "off" position, and when turned to the left or anti-clockwise from the vertical position shown in Fig. 3, the operation is hand controlled upwardly or downwardly. When main switch 24 is turned to the right or in a clockwise direction, the operation of the hoist motor is automatic upwardly or downwardly. When switch 24 is in the automatic position, and

switch 25 is turned to the right or clockwise, the hoist motor is automatically operated to lower the fork or load support as long as the light beam is intercepted and to stop movement of the motor when the light beam is beneath and no longer reflected by the load, the hoist motor being again started when a lift or sheets have been placed on the load and intercept the light beam. When switch 25 is turned to the left or anti-clockwise, the hoist motor is automatically operated to elevate the fork or load support as long as the light beam is unintercepted by the top of the load and to stop movement of the hoist motor when the load has moved up high enough to intercept the light beam and reflect it onto the photocell, which then functions to stop the hoist motor until a lift or sufficient sheets of the load have been removed from the top of the pile so as not to intercept the light beam, whereupon the photocell functions to start the motor again, thus moving the load upwardly in predetermined increments depending upon the adjusted elevation of the photocell.

In order to accomplish this, there is provided a housing 26, see Fig. 2, that is adjustable vertically on a post 27 mounted on a fixed supporting frame 28 and secured at its upper end as at 29 to the housing 31 containing the solenoids 21 and 22 and switch mechanism, which housing is mounted on the motor supporting frame and suitably tied to a vertical part of the truck frame. The housing 26 is provided with a lamp 32, reflector 33, and condenser lens 34, while 35 designates a condenser lens through which the light beam is reflected back from the top of the load onto the photocell 36 through a shield 37. The lamp mechanism and photocell unit are mounted on bracket 38, see Figs. 5 and 7, which carries a sleeve 39 that is slidable vertically on the vertical post 27, and 41 designates a handle connected to the sleeve 39 for adjusting the lamp mechanism and photocell vertically. These parts are held in their vertically adjusted position by a locking lever 42 that is pivoted to the sleeve 39 at 43 and held normally in locking position by a coil spring 44 connected to a pin 45 on the sleeve 39 and to the adjacent end of the locking lever 42, which has an opening 46, see Fig. 9, that embraces the vertical post 27. Locking lever 42 carries a dog 47 that frictionally engages the adjacent surface of post 27 and holds the lamp mechanism and photocell in their position of vertical adjustment. The locking lever 42 is further provided with an opening 48 that embraces a pin 49 on the handle 41 and is movable downwardly against the action of spring 51 to release the lever from engagement with the post 27 and permit vertical adjustment of the lamp mechanism and photocell when desired to change the elevation at which movement of the load is to be stopped.

The photocell and light mechanism are thus adjustable vertically to any point on the post 27 to determine the point at which the hoist motor is stopped automatically during upward or downward travel of the load, depending upon the direction in which it is desired to move the load support. Assuming that the load support is traveling upwardly, with the light mechanism and photocell at a given adjusted position, when the load reaches a point high enough to intercept the beam of light and reflect it back onto the photocell, the latter functions to stop the hoist motor. The load support then remains stationary until a lift or sufficient number of sheets have been removed from the top of the load so as to

no longer intercept the light beam, and when this happens, the light no longer being reflected onto the photocell, the latter, through the photo-electric relay and electrical mechanism to be described presently, operates the hoist motor which again raises the load support through the predetermined distance. This automatic cycle continues as long as switch 24 is set to "automatic" position and switch 25 is set to "raise" position, see Figs. 3 and 11, and when switch 25 is set to "lower" position with switch 24 remaining in the "automatic" position, the load support is automatically lowered through predetermined distances successively, being stopped each time the load is below the beam of light and automatically started when sheets have been placed on the top of the load sufficiently to intercept the beam of light.

In Fig. 11 is illustrated the circuit arrangement for governing the solenoids 21 and 22, either automatically or manually, as follows: The hoist motor 13 is connected to conductors 52 and 53 of the current supply line through suitable conductors 54 and 55 respectively, leading from conductors 52 and 53 to the reversing drum switch 16 already referred to, while 56 and 57 designate conductors leading from opposite sides of the line to the aforementioned main or central switch 24, which is of the double-throw type, see Figs. 3 and 11. When switch 24 is in the "off" position, as shown in Fig. 11, the hoist motor is idle and when switch 24 is turned to the right or clockwise, it completes the circuit through conductors 58 and 59 to automatic transformer 61, lamp 32, conductor 62 and contact 72. At the same time the circuit is completed through conductors 69 and 71 to the photoelectric relay 65, which when the photocell 36 receives the reflected beam, moves control switch 66 downwardly, the latter being held normally in its uppermost position, see Fig. 11, by a spring not shown, while photocell 36 is connected to the photoelectric relay 65 by means of conductors 67 and 68. The photoelectric relay is of conventional type and connected by conductors 69 and 71 to opposite sides of the line. The selector "automatic" switch 25, see Figs. 3 and 11, causes the load support to move upwardly or downwardly, depending upon its position, for automatic control of the hoist motor, and switch 23 permits moving the load support upwardly or downwardly, depending upon its position, for manual control of the hoist motor.

Fig. 11 shows the position of the parts when the main or central switch 24 is in "off" position, selector "hand" switch 23 in "off" position, and selector "automatic" switch 25 is turned to position to effect automatic raising of the load support when switch 24 is moved to the automatic position. In the position shown in Fig. 11, the photoelectric relay 65 is held in elevated position as already described, and switch 66 is elevated to the position indicated. When switch 24 is moved to the "automatic" or down position of Fig. 11, the circuit is closed through conductor 56, contact 72, and conductor 62 to the lamp mechanism, thence through conductor 58 and contact point 73 to switch 24 and to the other side of the line through conductor 57, also through conductor 62 to switch 25, contact point 74, switch 66, contact point 75, and conductor 76 to solenoid 21 which effects raising of the load support automatically until the light beam is intercepted by the top of the load and the beam reflected onto the photocell 36, causing the photoelectric relay 65 to move the switch 66 downwardly. This breaks the cir-

cuit to the hoist motor and stops elevating of the load support until a lift or a sufficient number of sheets have been removed so that the light beam is no longer intercepted by the top of the load, whereupon the photoelectric relay 65 is released and elevated by its spring to the position shown in Fig. 11, and the load support again elevated and the cycle repeated.

If it is desired to lower the fork or load support automatically, with switch 24 still in the "automatic" or down position referred to above, switch 25 is moved into engagement with contact 77, see Fig. 11, and assuming that the top of a load is in the path of the light beam, the photocell causes photoelectric relay 65 to move the switch 66 downwardly into engagement with contact 78, the circuit thus being completed through conductor 79 to solenoid 22 which operates to lower the load support until the top of the load has moved out of the path of the light beam which is then no longer reflected onto the photocell. This releases the photoelectric relay 65, permitting switch 66 to move upwardly to the position shown in Fig. 11, and breaking the circuit, thus stopping the hoist motor which remains idle until a sufficient number of sheets have been placed on top of the load to again intercept the light beam, which thereupon strikes the photocell, causing the photoelectric relay 65 to be actuated and moving switch 66 again downwardly, operating solenoid 22 to effect further movement of the hoist motor downwardly, and the cycle just described is repeated.

When switch 24 is moved to the "hand" position, referring to Figs. 3 and 11, for operation of the hoist motor by manual control, the circuit is from conductor 56 through switch 24, contact 81, and conductor 82 to the switch 23, which is movable upwardly into engagement with contact 83 for raising the load support and the circuit then completed through solenoid 21 to conductor 53 and the other side of the line, or downwardly into engagement with contact 84 to complete the circuit through solenoid 22 to lower the load support, and thence to conductor 53 or the other side of the line.

In this manner, the work or load support is movable automatically when switch 24 is set to the "automatic" position, switch 25 being turned to the right, referring to Fig. 3, for lowering the load support automatically, or to the left for elevating the load support automatically. When switch 24 is set to the "hand" or manual position, the load support is moved upwardly or downwardly by operating switch 23 to "raise" or "lower" positions respectively. The exact position at which the load support stops its travel in either upward or downward movement during automatic control depends on the vertically adjusted position of the lamp mechanism, which may be adjustable in any desired manner.

While the invention has been described with reference to the particular structure herein shown, it is not limited to the details illustrated, and this application is intended to cover such modifications or departures as may come within the purposes of the improvement and the scope of the following claims.

I claim:

1. A lift truck including a load support and a hoist motor connected thereto for raising or lowering the same, control mechanism operatively connected to the hoist motor, a photocell operatively connected to said control mechanism and arranged to receive a beam of light reflected

from a load on the load support, and lamp mechanism arranged and operating to project a beam of light toward a load on the support, said projected beam of light and said reflected beam being arranged at an acute angle to each other and the photocell and lamp mechanism being arranged on the same side of the support, the lamp mechanism operating to project a beam onto the load and the load acting to reflect the beam onto the photocell.

2. A lift truck including a load support and a hoist motor connected thereto for raising or lowering the same, control mechanism operatively connected to the hoist motor, a photocell operatively connected to said control mechanism and arranged to receive a beam of light reflected from a load on the load support, and lamp mechanism arranged and operating to project a beam of light toward a load on the support, said projected beam of light and said reflected beam being arranged at an acute angle to each other and the photocell and lamp mechanism being adjustable vertically and arranged on the same side of the support, the lamp mechanism operating to project a beam onto the load and the load acting to reflect the beam onto the photocell when the load reaches a predetermined level.

3. A lift truck including a load support and a hoist motor operatively connected thereto for raising or lowering the same, a control switch operatively connected to the motor, a photocell operatively associated with said control switch and arranged to receive a beam of light reflected from a load on the load support, and light mechanism operating to project a beam of light onto a load on the load support, said light beam being reflected by the load onto the photocell in a direction at an acute angle to the direction of the beam of light when the load is in the path of the projected light beam.

4. A lift truck including a load support and a hoist motor operatively connected thereto for raising or lowering the same, a control switch operatively connected to the motor and normally held in one position, a photoelectric relay governing the control switch and operable to move it to a second position, a photocell operatively connected to said photoelectric relay and arranged to receive a beam of light reflected from a load on the load support, and light mechanism operating to project a beam of light onto a load on the load support, said beam being reflected by the load onto said photocell in a direction at an acute angle to the direction of said projected beam of light when the load is in the path of the projected beam.

5. A lift truck including a load support and a hoist motor operatively connected thereto for raising or lowering the same, a control switch operatively connected to the motor and normally held in one position, a photoelectric relay governing the control switch and operable to move it to a second position, a photocell operatively connected to said photoelectric relay and arranged to receive a beam of light reflected from a load on the load support, and light mechanism operating to project a beam of light onto a load on the load support, said light mechanism and photocell being located on the same side of the load support and adjustable vertically, said reflected beam being arranged at an acute angle to the projected beam and acting to reflect the beam onto the photocell.

6. A lift truck including a load support, a hoist motor operatively connected thereto for raising or lowering the same, reversing means for oper-

ating the motor in either direction, and solenoids controlling said reversing means, a control switch governing said solenoids and normally held in one position, a photoelectric relay operatively connected to said control switch and operable to move it to a second position, a photocell operatively connected to said photoelectric relay and arranged to receive a beam of light reflected from a load on the load support, and light mechanism arranged and operating to project a beam of light toward the load, said beam being reflected onto the photocell in a direction at an acute angle to the direction of said projected beam of light when the load is in the path of the beam and the photocell and light mechanism being vertically adjustable.

7. A lift truck including a load support, a hoist motor operatively connected thereto for raising or lowering the same, and a reversing switch connected to said motor, solenoids operatively connected to said reversing switch, a photocell and light mechanism adjustable vertically on the truck, the light mechanism being arranged and operating to project a beam of light toward the load and the photocell arranged to receive the reflected beam of light when the load is in the path of said beam, said reflected beam being at an acute angle to said projected beam of light, a photoelectric relay governed by said photocell, and a control switch connected to said relay and governing said solenoids, said control switch being normally in one position and operated to a second position by said relay.

8. A lift truck including a load support, a hoist motor operatively connected thereto for raising or lowering the same, and a reversing switch connected to said motor and operable to move it in either direction, solenoids operatively connected to said reversing switch, a control switch movable to either of two positions and operable to actuate one or the other of said solenoids, a photoelectric relay operatively connected to said control switch and held normally in position to actuate the "raising" solenoid, a vertically adjustable photocell operatively connected to said photoelectric relay, and vertically adjustable light mechanism operating to project a beam of light onto a load on the load support, the load acting to reflect the beam of light onto the photocell, said reflected beam being at an acute angle to said projected beam of light and said photocell acting to control movement of the load support when the load is in the path of the beam.

9. A lift truck including a load support, a hoist motor operatively connected thereto for raising or lowering the same, and a reversing switch connected to said motor, solenoids connected to said reversing switch, a control switch movable to either of two positions and operating to actuate one or the other of said solenoids, a photoelectric relay operatively connected to said control switch and held normally in position to actuate the "raising" solenoid, a photocell operatively connected to said photoelectric relay, lamp mechanism operating to project a beam of light toward the load support whereby said beam is reflected onto said photocell when a load is in the path of the beam, said reflected beam being at an acute angle to said projected beam of light, an electric circuit connected to said hoist motor, lamp mechanism, photoelectric relay and solenoids, a selector "automatic" switch in said circuit movable to either "raise" or "lower" position operating to govern said control switch for raising or lowering the load support automatically, a selector "hand"

switch in said circuit operable to raise or lower the load support by manual control, and a main switch in said circuit operable to permit control of said solenoids either automatically or manually.

10. A lift truck including a load support, a hoist motor operatively connected thereto for raising or lowering the same, and a reversing switch connected to said motor, solenoids connected to said reversing switch, a control switch movable to either of two positions and operating to actuate one or the other of said solenoids, a photoelectric relay operatively connected to said control switch and held normally in position to actuate the "raising" solenoid, a photocell operatively connected to said photoelectric relay, lamp mechanism operating to project a beam of light toward the load support whereby said beam is reflected onto said photocell when a load is in the path of the beam, said reflected beam being at an acute angle to said projected beam of light, an electric circuit connected to said hoist motor, lamp mechanism, photoelectric relay and solenoids, a selector "automatic" switch in said circuit movable to either "raise" or "lower" position operating to govern said control switch for raising or lowering the load support automatically, a selector "hand" switch in said circuit operable to raise or lower the load support by manual control, and a main switch in said circuit operable to permit control of said solenoids either automatically or manually, said lamp mechanism and photocell being located on the same side of the load support and adjustable vertically.

35 11. A lift truck including a load support, a hoist motor operatively connected thereto for raising or lowering the same, and a reversing switch connected to said motor, "raising" and "lowering" solenoids connected to said reversing switch, a control switch movable to either of two positions and operating to actuate one or the other of said solenoids, a photoelectric relay operatively connected to said control switch and held normally in position to actuate the "raising" solenoid, said relay when actuated operating to move the control switch into position to operate the "lowering" solenoid, a selector "automatic" switch in the circuit with said control switch and movable to "raise" or "lower" position, said selector switch 50 when in "raise" position breaking the circuit to the "lowering" solenoid and when in "lower" position breaking the circuit to the "raising" solenoid, a photocell operatively connected to said photoelectric relay, and light mechanism arranged to project a beam of light onto the load on the load support and said beam being reflected onto the photocell in a direction at an acute angle to the direction of said projected beam of light when the load is in the path of the beam of light.

60 12. A lift truck including a load support, a hoist motor operatively connected thereto for raising or lowering the same, and a reversing switch connected to said motor, "raising" and "lowering" solenoids connected to said reversing switch, a control switch movable to either of two positions and operating to actuate one or the other of said solenoids, a photoelectric relay operatively connected to said control switch and held normally in position to actuate the "raising" solenoid, said relay when actuated operating to move the control switch into position to operate the "lowering" solenoid, a selector "automatic" switch in the circuit with said control switch and movable to "raise" or "lower" position, said selector switch 75 when in "raise" position breaking the cir-

cuit to the "lowering" solenoid and when in "lower" position breaking the circuit to the "raising" solenoid, a photocell operatively connected to said photoelectric relay, and light mechanism arranged to project a beam of light onto the load 5 on the load support and said beam being reflected onto the photocell when the load is in the path of the beam of light, said reflected beam being at an acute angle to said projected beam of light and said photocell and lamp mechanism being 10

vertically adjustable and located on the same side of the load support.

ARTHUR S. HAMILTON, JR.
